UNITED STATES PATENT OFFICE

WILHELM HOTZ, OF BASEL, SWITZERLAND

COMPRESSED AIR BRAKE WITH STAGE BRAKING

Application filed April 8, 1930. Serial No. 442,611.

The present invention relates to compressed air brake arrangements for railway cars, especially electric railway cars. In order to ensure that such railway cars will stop automatically when the engineer passes stop signals, semaphores etc., arrangements have been proposed previously for automatically effecting an outflow of compressed air from the brake apparatus, as by means of a lever 5 provided on the railway car coming into contact with stops.

The object of the present invention is to eliminate the disadvantages of known systems by providing an improved apparatus in which the braking action comes into operation in stages but at an adjustable speed and with an adjustable force. A further object of the invention is to provide improved means by which the emergency arrangement 10 is disengaged automatically when the engineer effects the braking operation. The installation according to the invention also has the further advantage that the emergency brake is brought into operation automatically 15 when the engineer by reason of accident, ill health or death etc. loses control of the train and no longer controls the brake arrangement.

In the accompanying drawings an example of construction is illustrated diagrammatically in Figs. 1 and 1a.

Figs. 2 and 3 show the controlling valve in sectional elevation and in a top view respectively.

Figs. 4 and 5 show in sectional elevation and in a cross-section the auxiliary valve.

In the underframe 1 of the vehicle a roller 2 is vertically movable in suitable guides by means of bearings. The said roller 2 is mounted in such a position that it can run on a brake actuating cam rail 3 mounted in the track. The rail 3 is adjustable vertically to cause the roller 2 to move upward in the guides 1 when running on said rail. The bearing of the roller 2 is connected by a link parallelogram 4, 5 to a stationary pin 6 of the underframe. A spring 7, connected to the members 5, tends to press the roller 2 downwardly. The parallelogram is connected by means of a rod 8 to the arm 9

of a cock 10 of a compressed air pipe 11. The pipe 11 is connected to the pipe 12, which pipe is connected to the compressed air supply pipe of the train. The brake mechanism shown is of the well known "Westinghouse" type, and is therefore not described in detail. To the pipe 11 is connected the lower end of a cylinder 14 provided with two chambers 15 and 16 separated by a partition provided with a restricted opening 17. The lower chamber 16 is partly filled with a liquid.

In the lower chamber 16 is provided a coiled spring 18 of which one end bears against the partition and the other end against a piston 19 having a rod 20. The spring 18 tends to press the piston 19 downwardly and to hold it in the position shown in the drawings.

The upper portion of the piston rod 20 has a rack engaging a toothed wheel 21, the latter being rigidly connected to a rotary valve disk 23 which controls the air outlet openings 28 of a casing 22. The latter is connected by a compressed air pipe 25 (main pipe) and the driver's brake valve (26) to the compressed air brake installation 27 of the train. The rotary valve 23 is provided with slots 28 of unequal length and unequal radial distance. When the rotary valve 23 is turned, air passes out of slots 29 of casing 22 and therefore out of the pipe 25 and thus further out of the brake arrangement 27 of the train. The outflow of air and hence also the braking action is effected in stages because the air escape is interrupted except when the different air outlet openings 28 register with and pass over their corresponding slots 29. The actuation movement of the brake blocks therefore is interrupted for short intervals a number of times, and in this manner the usual braking operation effected by hand (balancing the compressed air in the main pipe) is imitated.

To the valve 26 are connected in known manner the cylinders 30 serving to adjust the 95 brake blocks.

There is also provided a further cylinder 31, the piston rod 32 of which by means of a lever 33 and links 34 secured to the bearing of the roller 2, can raise the bearings of the 100

roller 2 and thus move said roller out of its position in readiness for operation. The discharge of compressed air by the valve 26, causes the cylinder 31 to operate elements 5 32, 35 and thereby raise the roller as will be understood. If the engineer by means of the brake valve 26 applies the brakes of the train the arrangement 11—25 does not come into operation because owing to the position of 10 the brake valve 39 the connection between the pipes 12 and 11 is interrupted.

The connection of this auxiliary device 14 to valve 29 is effected for example in the case of the Westinghouse driver's brake valve 26 15 by means of the pipe 12 which is attached at the existing blind socket member 50 adjacent the usual pressure regulator. Said valve is also attached to the air tank 27^a as usual. On the driver's brake valve 26 of the Westinghouse rapid brake there is in accordance 20 with this invention made a modification by which the pipe 12 also communicates with the main air tank 27^b by the pipes 27, when the handle 51 of the valve 26 moves within 25 its filling position, denoted by the numbers I, II (Fig. 3). This modification consists in that opening 33 (which in the standard construction of the "Westinghouse" valve is only a circular port) is converted into an elongated 30 slot, as shown, so that the pipe 12 through the connection 50 and hence also the whole auxiliary device according to this invention communicates with the supply mains of compressed air of the installation throughout the 35 period in which the engineer moves the handle 51 of valve 26 between the limits I, II. The said communication is interrupted as soon as handle 51 is moved into the braking position III of valve 26, or into the emergency position IV—V, because the slot 53 is then out of communication with the pipe 12.

Between the pipe 12 and the pipe 11 there is provided a by-pass pipe 38 fitted with a valve 39, which is normally held in closed 40 position by a suitable spring (not shown). Said valve may be actuated manually by means of a hand lever 40 and a pedal 41. This arrangement serves as a substitute for the so-called dead man's lever. If the engineer releases the lever 40 and pedal 41 for any reason the by-pass pipe 38 is opened, compressed air from the pipe 12 passes into the cylinder 14 and the brakes of the vehicle and thus of the train are then applied automatically by 50 the piston 19, cylinder 14, auxiliary valve 22 and their connections, hereinbefore described and as will be understood.

There is also provided a rod mechanism 42 connected to the trolley 43 and to a cock 44 in 60 order to lower the trolley 43 when the emergency arrangement operates, as a result of which the locomotive is cut out of circuit and when travelling into a station transmission of current from the line section to station 65 mains cannot take place.

As soon as the engineer moves his brake valve 26 into the filling or releasing position the auxiliary device 14 again returns to its position ready for operation because the spring 18 forces the piston 19 downwardly to 70 the normal position shown in Fig. 1, owing to the reduced air pressure below the piston incident to such operation of the engineer's valve.

The adjustment of the brake actuating rail 75 3 may be effected in any suitable manner. It may be connected to the usual signal setting mechanism and it may also be released by any other suitable distant operation. Further the rail 3 may also be set by the trains 80 themselves by means of setting bars in order to thus obtain a block safety. When the roller 2 runs onto the set rail the roller is raised against the action of the spring 7 and the valve 10 is opened by means of the parallelogram links 4, 5, the rod 8 and the member 9. Compressed air enters the cylinder 14 below 85 the piston 19. The latter is moved against the action of the spring 18. Liquid is thus forced through the opening 17 in the partition. The piston moves more slowly or more rapidly according to the size of the opening in the partition. The rotary valve 23 is therefore turned at a selective speed. In this manner the braking action is also predetermined as regards time and power. To the rod 20 may also be connected a switch 46 of a circuit 45 controlling the driving motors (releasing coil) for example in such a manner 90 that the latter are disconnected from the drive before the braking action commences.

What I claim and wish to secure by the U. S. Letters Patent, is:

1. In air brake apparatus, a brake pipe, fluid pressure actuated apparatus connected thereto and including a movable element, an engineer's valve, and an emergency valve including a casing connected pneumatically with the engineer's valve for the discharge of air from the latter, and also including an element actuated by the movable element of said fluid pressure apparatus, said emergency valve being constructed and arranged to successively and intermittently discharge compressed air from the brake apparatus through the engineer's valve during a single movement in one direction of the said movable element of the said fluid pressure actuated apparatus, and means, independent of the engineer's valve to establish communication between the said brake pipe and said fluid pressure actuated apparatus, to cause the latter to operate and hence cause the brakes to be applied by the emergency valve in the event of failure 115 of operation of the engineer's valve.

2. Apparatus as claimed in claim 1, including a fixed prime moving track member and train carried means including a member actuated by said prime moving track member to 120

automatically supply compressed fluid to said valve actuated means.

3. Apparatus as claimed in claim 1, in which the fluid pressure actuated means is a cylinder to which the brake pipe is connected and having a partition provided with an opening, a piston in said cylinder below said partition and coacting with the cylinder to form a fluid containing chamber to retard the valve actuating stroke of the piston.

4. Apparatus as claimed in claim 1, in which the fluid pressure actuated means is a cylinder to which the brake pipe is connected and having a partition provided with an opening, a piston in said cylinder below said partition and coacting with the cylinder to form a fluid containing chamber to retard the valve actuating stroke of the piston and also including a spring active to impart reverse stroke to the piston.

5. Apparatus as claimed in claim 1, in which the emergency valve comprises a casing having an air exhaust port and a plurality of air supply ports and also includes a revoluble valve disc having a plurality of ports arranged to successively come into registry with the air supply ports of the casing.

6. Apparatus as claimed in claim 1, including means to automatically supply compressed fluid to the fluid actuated means and also including an engineer's valve connected to the air brake system and also connected to the first named valve, said engineer's valve being constructed and arranged to automatically cut out connection between the first named valve and the brake pipe when the engineer's valve is moved to braking position or to emergency position.

7. Apparatus as claimed in claim 1, including a fixed prime moving member and train carried means including a member actuated by said prime moving member to automatically supply compressed fluid to said valve actuated means and also including an engineer's valve and compressed fluid actuated means controlled by the engineer's valve to move the train carried member to inoperative position.

In testimony whereof I affix my signature.

WILHELM HOTZ.
